UNITED STATES PATENT OFFICE

100,082

DESIGN FOR AN ELECTRICAL FLOOR FITTING

Joseph William Wiesmann, Pittsburgh, Pa., as-
signor to H. H. Robertson Company, Pittsburgh,
Pa., a corporation of Pennsylvania

Application September 13, 1935, Serial No. 58,546

Term of patent 14 years

To all whom it may concern:

Be it known that I, Joseph William Wiesmann, a citizen of the United States, residing at Pittsburgh, in the county of Allegheny and State of Pennsylvania, have invented a new, original, and ornamental Design for Electrical Floor Fitting, of which the following is a specification, reference being had to the accompanying drawing, forming a part thereof.

In drawing, Fig. 1 is a front elevation; Fig. 2 is a side elevation; and Fig. 3 is a plan of an electrical floor fitting showing my new design.

The dominant feature of my design resides in the portion illustrated in solid lines.

I claim:

The ornamental design for an electrical floor fitting, as shown and described.

JOSEPH WILLIAM WIESMANN.
